UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

FRICITION DRAFT-RIGGING.

1,192,572.

Specification of Letters Patent.

Patented July 25, 1916.

Application filed January 3, 1913, Serial No. 739,952. Renewed December 30, 1915. Serial No. 69,470.

To all whom it may concern:

Be it known that I, ERNEST H. SCHMIDT, a citizen of the United States, residing at Cleveland, Cuyahoga county, Ohio, have invented new and useful Improvements in Friction Draft-Rigging, of which the following is a specification, reference being had to the accompanying drawings, in which—

Figure 1 is a plan of my improved rigging, partly in section, showing its application to a railroad car; Fig. 2 is a longitudinal vertical section; Fig. 3 is a section on lines III—III of Fig. 1, and Fig. 4 is a section on lines IV—IV of Fig. 1.

My invention relates to friction draft rigging and consists in providing telescoping casings combined with the frictional mechanism coöperating with one of the casings, and in the parts hereinafter particularly described.

Referring to the drawings, 2 indicates an inner casing or friction barrel of cylindrical form, which has an enlarged portion 3 formed integral therewith, which is adapted to abut against the draft sill stops 4 attached to the draft sills 5 of the car structure. Seated within the rear of the casing 2 are the springs 6 and 7, the spring 7 being located within the spring 6 and both of which abut at their rear ends against the rear of the casing 2. The forward end of the spring 6 bears against the rear flat face of the rearmost cone ring 8, and forwardly of this cone 8 are the cone rings 9 and the cone ring 10. The ring 10 bears against the front follower or outer casing 11. The cones 8, 9 and 10 are spaced apart by a plurality of segmental rings 12, which have a frictional bearing against the interior of the inner casing 2, and which, with the casing 2, comprise the frictional elements of the rigging. The conical or wedging face of each cone ring is in bearing engagement with the corresponding conical faces of the adjacent segmental rings and has bearing faces of the same inclination as those of the adjacent faces of the segmental rings. Abutting against the cone 10 and within the cone rings, is a plunger or releasing member

13 which has an operating engagement with the inner or releasing spring 7. Upon the releasing member 13 are shoulders 14 and

15, which are adapted to bear against corresponding surfaces on the cones 9 and act to drive them toward the open end of the 55 casing 2 to release their wedging engagements with the segments 12 upon the completion of the buffing or draft stresses.

The outer casing 11, which also comprises the front follower, is cylindrical in form 60 and is adapted to telescope with the inner casing 2. Upon the periphery of the inner casing 2 are arranged a plurality of pockets 16, in which are seated the rear ends of the springs 17, and upon the periphery of the 65 outer casing 11 are also arranged a plurality of pockets 18, corresponding to the pockets 16, within which are seated the forward ends of the spring 17.

The outer casing or front follower 11 is 70 preferably rectangular in form and bears against the forward draft sill stops 19.

The numeral 20 indicates the usual form of yoke which is secured to the coupler shank 21.

When under draft or buffing strains the two casings will telescope, thus compressing the springs 17, as the friction segments and wedge rings are driven into the inner casing, and when the pressure is relieved the 80 springs 17 will drive the outer casing, and with it the coupler, outwardly to normal position, thus permitting the wedges and segments within the inner casing to be restored to normal position by the springs 6 85 and 7.

It is obvious that my invention may be used with draft riggings of various forms and constructions, and that many changes may be made therein, since

What I claim is:

1. In a draft rigging, a barrel, frictional and spring mechanism contained therein, a follower arranged externally of the barrel, and spring mechanism on the exterior of 95 the barrel adapted to restore the follower and the coupler to normal position after buffing or draft.

2. In a draft rigging, a barrel, frictional and spring mechanism contained therein, a 100 follower having a telescopic engagement therewith, the follower and barrel having longitudinally extending registering chambers disposed around the central axis of

the frictional mechanism, and separating springs between said barrel and follower seated in said chambers.

3. In a draft rigging, telescoping casings, one of said casings comprising a barrel, and containing spring and frictional mechanism, and the other of said casings being adapted under the impact of buffing or draft to force the friction mechanism rearwardly of the

casing, and spring mechanism disassociated 10 from the friction mechanism for moving the casings relative to each other after buffing or draft.

ERNEST H. SCHMIDT.
